United States Patent Office

Des. 212,432
Patented Oct. 15, 1968

212,432

DOLL

Reuben B. Klammer, 245 S. Barrington,
Los Angeles, Calif. 90049

Filed Apr. 14, 1967, Ser. No. 6,684

Term of patent 14 years

(Cl. D34—4)

I claim:

The ornamental design for a doll, substantially as shown.
